DRAINAGE CONTROL MEANS FOR DISHWASHING APPARATUS AND THE LIKE

John L. Andrews, Oak Park, Ill., assignor to General Electric Company, a corporation of New York

Application November 1, 1951, Serial No. 254,288

1 Claim. (Cl. 134—186)

This invention relates to an improved method of controlling the drainage of washing and rinsing liquid from dishwashers and like apparatus.

Broadly speaking, my invention is applicable to any apparatus in which quantities of liquid are periodically circulated within a vat and drained therefrom. Dishwashing apparatus is a typical example, for under control of a time-cycle switch, water for rinsing and washing the dishes is brought into and drained from the tub. A presently commercially successful domestic electric dishwasher includes a vat or tub within which are placed the dishes and utensils to be washed, means for automatically introducing into said vat a measured quantity of water, a motor driven impeller to circulate the water forcefully over and about the articles being washed, and valve controlled means for draining the water at the end of a washing or rinsing operation. Comparatively little water—usually only about twelve pints—is used for the respective washing and rinsing operations, and it has heretofore been considered essential to use drainage valves or equivalent mechanisms which positively close against loss of water during these operations. These valve devices are normally automatically controlled by a time-cycle switch or the like for operation at appropriate times during the operation of the apparatus; and although the valves are generally very reliable, they are potential sources of trouble in that their operating mechanisms may become deranged after long use or the valves themselves become clogged with particles of food waste and fail to close completely.

It is therefore a principal object of this invention to provide means whereby the drainage of liquid from a vat may be satisfactorily controlled without drain valves.

It is another object of my invention to provide a dishwasher or the like which does not utilize drain valves; which operates substantially without loss of liquid during the washing and rinsing operations, and which provides for complete drainage or discharge of liquid when required by the operational cycle.

It is a further object of my invention to provide a dishwasher having an improved drainage system.

It is still another object of my invention to provide a dishwasher drainage system in which a clogged sewer or waste outlet will not result in leakage of water on to the floor of the building even though during such clogged condition liquid may be leaving the dishwasher under pump pressure.

Yet another object of my invention is to provide an improved impeller for a dishwasher.

It is still another object of my invention to provide a dishwasher having a free-draining vat and a rotatable impeller for circulating water throughout the vat, there being such relationship between the impeller and the adjacent wall of the vat that the rotation of the impeller prevents the water from leaving the vat.

During extensive studies of water flow and the pattern of recirculation in dishwashers of the impeller type it was

2

observed that as the water cascades from the dishes and walls of the washing vat and returns to the impeller for recirculation thereby, the rapidly rotating impeller blades scoop up a substantial depth of the water layer immediately about the impeller hub and throws it upwardly and away from the impeller. I then discovered that by a suitable relationship of the lower hub portion of the impeller to the bottom wall of the tub, desirably, although not necessarily, supplemented by the addition of structure about the base portion of the impeller hub to provide an outwardly directed pumping action, the lowermost layer of water may be kept from flowing beneath the impeller hub so long as the impeller was rotating; and by transferring the drainage port of the dishwasher from the usual location remote from the impeller to a position within the confines of the impeller hub it was found that the impeller itself could be made to operate as an efficient drainage control. No water reaches the drain port while the impeller-pump combination is in operation, and yet normal gravity drainage to the waste line, or alternatively, drainage to a sump supplying an impeller pump for discharging the water forcibly through a drainage system, occurs when impeller operation ceases.

In a presently preferred embodiment of my invention in which gravity drainage is contemplated, I provide a cluster of drainage openings at the bottom of the vat, said openings all being within the area of influence of the drainage-control means during operation thereof. Clearance is provided between said drainage control means and the bottom of the vat to permit food soil to pass to the drainage ports during the drainage operation. To reduce the possibility of scooping up food soil from the bottom of the vat and hurling it against the dishes being washed, the water circulation blades of the impeller are located at a higher level relative to the vat bottom. In a simple, effective, construction, the lower portion of the hub is provided with a plurality of angularly disposed slots which establish pumplike blades effective when the hub is rotating rapidly to drive the water outwardly along the bottom of the vat and thus prevent it from flowing beneath the hub and into the drain ports. When the impeller stops, however, the water may freely reach the drain ports for flow to a plumbing waste line.

In dishwashers of the so termed "pre-plumbed" type, the spent washing and rinsing waters must be pumped from the dishwasher to a waste pipe inlet located substantially above the maximum free water level of the dishwasher vat, and in accordance with accepted plumbing code requirements means must be provided to insure that no polluted water will be syphoned or otherwise flow from the waste line into the dishwasher vat. Suitable protection against such an occurrence may be had by providing a suitable vertical air gap between the overflow level of the waste pipe inlet and the end of the discharge conduit of the dishwasher. It is common experience, however, that plumbing waste lines may become clogged; and in such a circumstance the discharge from the dishwasher would overflow through the air ports and fall to the floor. As a feature of my invention, I have provided a discharge fitting or guard valve which not only provides the necessary air gap to prevent pollution as above noted, but prevents spillage of water through the air ports. Novel means are provided to set up a recirculation from the dishwasher vat to the discharge fitting and then into the vat whenever the pump operates during a period in which the drainage fitting is closed to prevent such backsiphonage and spillage as above noted.

Other features and advantages of my invention will be apparent from the following detailed description of presently preferred embodiments thereof read in conjunction with the accompanying drawings, in which Fig. 1 is a side

elevation of a dishwasher embodying one form of my invention, certain portions of the apparatus being in section and other portions being broken away to reveal underlying structure; Fig. 2 is a plan section taken through the base of the impeller hub on lines 2—2 of Fig. 1; Fig. 3 is a somewhat schematic elevation of the impeller indicating a water-circulation action while the impeller and its associated drainage control pump are rotating; Fig. 4 is a plan section of the drainage sump, taken on lines 4—4 of Fig. 1; Fig. 5 is a front elevation of a dishwasher of the "pre-plumbed" type, showing a form of drainage system and the anti-backflow discharge fitting and recirculation means; Fig. 5A is a structural detail showing a method of securing the sump to the dishwasher vat; Fig. 6 is an enlarged vertical section of the anti-backflow device and recirculation system; Fig. 6A is a somewhat schematic front elevation showing a manner in which dishwasher of Fig. 5 may be connected to the drain line of an adjacent kitchen sink; and Fig. 7 is a plan section taken through the pump chamber on lines 7—7 of Fig. 5.

Referring now to Fig. 1, a dishwashing machine 1 includes an outer casing 2 within which is securely supported a tub or vat 3. The dishwasher is of the front opening type; for example, it may be similar to that shown in U. S. Patent 2,422,022, issued June 10, 1947, to N. H. Koertge. Accordingly, the front wall portion (not shown) of the vat has a large opening which is served by a bottom-hinged door 4. As is well known, the door may be swung outwardly to a substantially horizontal position; whereupon dish and utensil-receiving racks (not shown), slidably supported on spaced side rails such as the rail 5, may be drawn out of the vat on to the door, loaded with dishes and the like to be washed, and returned to the vat. Then after closing the door, a timer-motor operated time-cycle switch 6 may be operated to conduct the dishwasher through a series of automatic operations including steps of rinsing, washing, rinsing, and final drying. Such controls and operational cycles are well known; see for example the typical form shown in Patent No. 2,536,256, entitled "Program Selector Switch," granted January 2, 1951, to Ralph L. Berg, and assigned to my present assignee. The broad aspects of dishwasher construction and control form no part of the present invention. It is therefore believed sufficient merely to note that water is introduced into the vat through an inlet fitting 7 served by a solenoid or other electro-motor operated valve assembly 8 which receives water through one or more pipes 9 and conducts it through a conduit 10 to said inlet fitting. A motor 11 suitably mounted below the vat has its shaft 12 extending vertically within a guard tube 14 for secure attachment to the transverse wall of the hub 16 of an impeller 17, which is preferably substantially as shown in the above noted Koertge Patent 2,422,022. The impeller is thus mounted for rotation at motor speed. Impeller 17 has water circulation blades 18 and air circulation blades 20, the latter enforcing air flow over and about a ringlike heating element 21 of generally circular shape and having terminal portions (not shown) for connection to the electrical system of the apparatus. It is understood that the apparatus will be connected through its control switch 6 to the conventional 115 volt alternating current system of the residence or other building in which the dishwasher is located. The heating element 21 is preferably of the sheathed conductor type as shown and described in the U. S. Patent to C. C. Abbott, No. 1,367,341, dated February 1, 1921.

The several operational cycles of a dishwasher of the above-noted type may be somewhat as follows: after placing the dirty dishes, etc., in the vat and loading a detergent dispenser (not shown) the door 4 is closed and latched and the switch 6 moved to operative position. Appropriate electrical circuit conditions are thereupon automatically set up in pre-established schedules to operate the electrical components of the apparatus. For ex-

ample, water sprays from fitting 7 for approximately 45 seconds to flush off food waste from the dishes; the impeller is quiet throughout this water inflow period. This first rinse water is drained. Then, with the impeller rotating, a measured quantity of water is admitted through fitting 7 and the dishes are subjected to a five-minute washing period, means (not shown) being provided for automatically adding detergent to the water during this operation. This wash water is then discharged to the drain, and a second washing operation of similar duration and nature occurs. After draining this wash water, water is admitted for two separate one-minute rinses, during each of which the impeller is rotating so that the dishes are subjected to thorough rinsing action under impeller power. The rinse water is drained after each rinse step. The final rinse is followed by an extended drying period during which air warmed by the heating element 21 is circulated throughout the vat by the air fan blades 20 of the impeller. After the initial 45-second water inflow, the quantities of water admitted to the vat for the subsequent washing and rinsing operations are substantially uniform. Although "time-fill" methods may be used for measuring the water inflow, such methods are subject to error because of variations in water pressure in different installations. Accordingly, it is preferred to use the "measuring coil" method disclosed and claimed in the W. L. Merrill U. S. Patent No. 1,995,318, granted March 26, 1935, for "Dishwashing Apparatus." As disclosed therein, the current drawn by the impeller motor increases as the water increases in depth and thus imposes a greater load on the impeller. At a level of electrical energy corresponding to the load imposed by the desired quantity of water, an electromagnetically operated switch in the motor circuit operates to establish a circuit to the solenoid-actuated water valve which closes said valve.

It has previously been noted that conventional dishwashers have employed mechanically or electro-mechanically actuated drain valves to control the discharge of the spent washing or rinsing liquid. The valveless construction disclosed and claimed herein operates on the basis of utilizing pumping action associated with impeller action to prevent water from reaching the always open drain ports; in other words, water can enter these ports only when the impeller is quiet following washing and rinsing operations. In furtherance of this operation, I construct the bottom wall 22 of the vat with a very gradual slope toward the impeller hub, and may also terrace the outer wall areas of the vat bottom, as indicated at 23, to prevent the water cascading down the side walls of the tub from flowing at a rapid rate directly to the impeller.

In the gravity drain arrangement of Fig. 1, a sump 24 is suitably secured to the bottom of the vat in watertight relation therewith. The sump has an outlet 25 to which may be attached a conventional plumbing drain trap 26 for connection to a branch of the plumbing waste line piping 27 serving the building, as is well understood. It may be mentioned here that the trap is shown in its Fig. 1 location only for purposes of illustration; the actual arrangement within the dishwasher casing would, of course, be that most accessible for installation and repair. Wall 22 of the vat 3 is provided with an opening co-axial with the hub 16 and guard tube 14. As shown in Fig. 2, it provides a suitable plurality of drainage openings 28. The guard tube 14 may advantageously be independent of the sump structure; for example, it may be a tube having a bottom bell secured in watertight relation to the bottom of the sump by a grommet 30 of elastomeric material clamped in position by a suitable number of machine screws or equivalent 31. The guard tube extends well above the maximum free water level of the dishwasher, thus making it unnecessary to provide water seals or the like about the motor shaft.

It is seen from Fig. 1 that the lowermost margin of the hub 16 is above the wall 22 and therefore water may pass

beneath the hub to flow through the ports 28 into the sump and vents to the trap 26 and waste line 27. In practice, the clearance between the hub and wall 22, and the size of ports 28, provide for free passage of food soil particles such as small pieces of lettuce and other leafy vegetables, etc.

The drainage control means now to be described may, of course, be physically independent of the impeller, although it is economical and effective to form it as an element of the impeller itself. This has operational as well as structural advantages, for it will be noted that said control means operates together with the impeller, and a unitary construction makes it possible to employ a single driving connection between the impeller and motor.

As is conventional, the impeller 17 is preferably molded from thermo-setting plastic materials. In the Fig. 1 embodiment the drainage control structure occupies the lower edge portion of the impeller—that is, the wall surface below the entering edge of the blades 18—which is made substantially thicker than the remainder of the hub wall. As best shown in Fig. 2, this thickened wall portion is subdivided into a plurality of segments 32, each of which operates as a pump element. The spacing of adjacent elements affords passages through which water may reach the interior of the hub and the drainage openings 28. I have found that although the shape and relative angle of the end walls of the respective segments 32 are not critical, excellent results are obtained when the leading wall 33 of each segment inclines sharply rearwardly with respect to the direction of rotation of the impeller. The trailing wall 34 is sloped as desired to provide a wide entrance mouth for the passages defined by the leading and trailing walls of the adjacent segments. Its angle with respect to the direction of rotation does not appear seriously to influence the action of the impeller presently to be described. An effective design results when the surface of each wall 33 is substantially tangential to the inner wall of the hub, and the walls 34 are so sloped that a diameter of the hub passing through the radially innermost end portions of the walls 33 will pass the radially outermost end portions of the walls 34 of the adjacent pump element. This arrangement gives strength and mass to the individual elements, provides a wide entrance mouth and a throat for each passage sufficiently large to admit reasonably large food soil particles into the drainage area within the hub, and improves the action of the hub in the surrounding water. With the impeller driven in counterclockwise rotation by the motor 11, as indicated in Fig. 2, the attack angle of the leading walls 33 will throw water away from the hub in a generally rearward direction as respects the rotation of the hub. The trailing walls 34 cannot conflict with this action because no water can be thrown forwardly of a line normal to the surface of wall 33, and as above noted, the outermost edge of the trailing walls 34 does not extend appreciably beyond such a line. The most important design aspect, of course, is for the lower portion of the hub to intercept the flow of water and direct it away from the drainage openings. Other impeller designs capable of adequately performing this function are possible. The foregoing specifications relative to the angle and disposition of the leading and trailing surfaces of the pump elements 32 are illustrative only and are not intended in any restricted sense.

The operation of the rotating impeller and its associated drainage-control pump is schematically shown in Fig. 3. Water draining from the dishes and side walls of the vat accumulates about the impeller hub to a depth which will submerge the leading or attack edges of the impeller blades 18. An upper layer of water will, therefore, immediately be thrown upwardly into the vat by the rapidly spinning impeller. That below the blades 18 will be repelled by the pumping action of the surfaces 33. As this water stratum flows away from the hub along the gradually rising bottom wall 22 of the vat, it loses

momentum because it is flowing countercurrent to the main water body. The eventual turbulence and intermixture terminates the stratification, and water which has been expelled by the surfaces 33 outwardly along the substantially flat bottom 22 of the tub will rise and be caught by the impellers 18 and thrown upwardly and outwardly thereby. The pumping surfaces 33 intercept water attempting to flow to the drainage ports, and therefore during washing and rinsing cycles in which the impeller is rotating very little water is lost. To drain the water from the vat between the several washing and rinsing cycles above noted, it is necessary only for the impeller to stop for a sufficient time to permit the water to drain into the sump, whence it flows to the drain trap and waste line. Accordingly, the time-cycle control 15 6 will provide for the necessary interruptions of the motor circuit.

The automatic dishwasher shown in partially sectional front elevation in Fig. 5 may be considered to be the 20 same as that of Fig. 1 in all essential structural details and basic equipment. Instead of draining spent washing and rinsing liquid by gravity, however, the dishwasher is equipped with pumping means by which the liquid may be discharged to a waste line connected to the waste line 25 of some adjacent fixture. For example, as shown in Fig. 6A, the dishwasher waste line may be connected to the trap of an adjacent kitchen sink. Dishwashers of this type are advantageous for installation in houses where the existing plumbing facilities do not readily lend 30 themselves to direct connection to a standard waste trap such as the trap 26 of Fig. 1.

In this second embodiment, the impeller 40 has a relatively large diameter substantially cylindrical hub 41 from which extend conventional water circulation blades 42 and 35 air circulation blades 43. Instead of forming the impeller with a relatively thick lower hub portion as in Figs. 1 and 2, I have provided the hub with a ring 44 adhesively or otherwise secured to the inner wall of the hub and projecting slightly downwardly therefrom as clearly appears in Fig. 5. It will be understood that the portion of 40 the ring below the hub will be formed with pumping sectors as in Fig. 2 and that the bottom wall 22 of the vat has drainage ports 28 as previously described.

A sump 45 is substantially deeper than the sump 24 of 45 Fig. 1; for reasons later appearing, the sump should accommodate the entire quantity of liquid used during any washing or rinsing operation. The sump may be removably attached to the bottom wall 22 of the vat by machine screws or equivalent 47 and an interposed gasket 48, as shown in Fig. 5A. As previously, a guard tube 50 extends from the bottom of the sump to a level well above the free water level in the washing vat to make it unnecessary to use stuffing boxes or the like about the motor shaft 51.

A plate 52 suitably secured within the sump 45 provides 55 a lower pump chamber 53. An outlet 54 is preferably tangential to chamber 53 pursuant to conventional impeller pump construction. A suitable impeller pump may advantageously comprise a cast tubular hub 55 having an end wall 56 which may seat securely on a shoulder 57 60 provided on motor shaft 51. A convenient method of securing the hub for rotation by the shaft is by a drive key (not shown) and nut 58. The impeller 40 may be securely fastened to shaft 51 by a nut 60 utilizing a lock washer or any other conventional means to prevent the nut from loosening during the operation of the apparatus. It will be noted that the guard tube, pump hub, and impeller hub are concentric and that the impeller hub passes through a suitable opening 61 in plate 52 providing an 65 annular passage through which liquid draining from the vat may reach the pump chamber 53. The pump blades 62 may be integral with hub 55 as is conventional and may be of any suitable shape, see Fig. 7. As will later appear, the pump need not develop much head. The pump chamber discharge 54 connects by means of a conventional 70 coupling nut 63 to a riser 64 secured to the outer wall of 75

vat 3 by a clamp 65 or other suitable means. Riser 64 terminates in a downwardly directed elbow 66.

I have indicated at 67 a vertical portion of a waste line branch which connects to the drain line of an adjacent kitchen sink (see Fig. 6A). Means are provided to prevent any possibility of sewage water from returning to the dishwasher vat in the event that the waste piping becomes clogged to the extent that water would back up in the waste line portion 67; and means are also provided to prevent such water from overflowing onto the floor of the building. As shown in Figs. 5 and 6, I provide a guard valve 68 having a plurality of valves which close in a predetermined order against backflowing liquid. Specifically, the presently preferred guard valve has a large diameter cylindrical body 69 (Fig. 6) fitted with an outlet 70 which may be attached to the waste line 67 by a conventional coupling nut; said body may be provided with an encircling clamp 72 by means of which the body may be secured to riser 64 in concentric alignment with the mouth of elbow 66. The upper end of body 69 is bellied for the telescopic reception of a cup 73 having a transversely extending bottom wall 74 provided with a central opening 75. The side wall of cup 73 has a suitable plurality of relatively large area air ports 76 which, as is obvious, will prevent any possibility of siphonage out of the branch waste line 67. To guard against the possibility of dishwasher drainage escaping through ports 76 as it flows about the valve elements within the cup 73, I employ a funnel-like structure 77 which projects below the level of said air ports, as clearly appears.

For valve elements of the guard valve 68, I use a spherical flotation valve 78 and a disc-like valve 80, the latter being slidably carried on the end of a stem 81 extending from a pole of the sphere 78. It will be noted in Fig. 6 that stem 81 only partly enters the bore 82 in the body portion of valve element 80; said valve element is supported on a light coil spring 83 resting on sphere 78. Valve element 80 has a sloping skirt portion 84 which under circumstances presently described, seats against the lowermost edge of elbow 66. The normal position of the respective valve elements is established by suitable means such as a wire or guard 86 supporting the sphere 78.

The operation of the instant dishwasher is similar in all respects to that of the previously described embodiment with one important difference: when washing or rinsing liquid is to be discharged, the impeller must be stopped for an interval to permit drainage through ports 28 into the sump 45 and then restarted while the liquid is being discharged from the sump. As previously noted, the sump accommodates the entire quantity of liquid used in any one washing or rinsing operation. When the motor is restarted, liquid is pumped into riser 64 and ultimately passes downwardly over the valve disc 80 through the funnel opening and valve openings 75 into valve body 69 and then through branch 67 to a T fitting 86 in the drain line from the adjacent sink 87. The sink drain line has a conventional trap 88 connecting to the waste piping (not shown) of the building. The dishwasher vat may be completely emptied into the sump in a very short time, and it is only necessary to provide a short interruption of operation before the admission of new liquid to the vat under control of the time-cycle switch. The impeller will, of course, be operating during the admission of new water to prevent it from entering the sump. Therefore, the spent time within the dishwasher sump may be disregarded as the new liquid is entering. If the plumbing trap became clogged, it is quite possible that liquid will remain in the branch 67 and any later discharge from the dishwasher could easily fill the guard valve body 69. If it were not for the air ports 76, polluted water could siphon back into the dishwasher, for as is clearly evident in Fig. 6A, riser 64 forms the necessary long leg of the siphon. The respective valves 78 and 80 not only mechanically prevent any backflow from valve body 69 into

the dishwasher but, particularly with respect to valve 78, prevent the liquid from overflowing through the air ports 76. It will be apparent that if the liquid level rises sufficiently to float sphere 78, the rising sphere will carry the valve disc 80 upwardly until the skirt portion 84 thereof seats against the bottom of elbow 66. As presently explained, this becomes immediately effective to throttle further discharge from said elbow even if the pump remains in operation and eventually seals the end of the elbow sufficiently to halt any further flow. However, at the initial stage of operation under clogged drain conditions, water may continue to enter the valve body 69 either from elbow 66 or by flowback through branch 67 and float 78 will seat against the rim of opening 75 to prevent any flow of liquid from branch 67 upwardly through the opening for spillage over the air ports 76. Spring 83 is sufficiently light to permit this upward movement of sphere 78 to seated position, and as the spring compresses, it urges valve disc 80 more firmly closed. To recapitulate, valve disc 80 seats as the float 78 rises, and it seats before float 78 comes into seated position in the orifice 75.

Although the drain pump is designedly incapable of producing a much greater head than is necessary to carry the waste over the elbow 66, it must be remembered that the valve 80 is at best only relatively lightly seated and may be incapable of preventing leakage into cup 73 under pump pressure conditions. I therefore provide for recirculation of the water whenever the pump is operating under clogged water line conditions. Specifically, I install within riser 64 a return tube 90 having a vertically extending inlet end 91 which is preferably concentric within the riser, and a downwardly sloping portion which passes through the wall of the riser to terminate at an opening 92 within the vat 3. A guard plate 93 is welded or otherwise secured to the wall of the vat to prevent water discharge from tube 90 over the dishes within the vat. The guard preferably has upper and lower openings 94, although it will be apparent that only the lower openings are essential.

During normal operation—that is, when the respective valve elements of guard valve 68 are in open position—water being pumped upwardly through riser 64 merely flows about the end 91 of the tube 90 without entering it. The aspirator action of water flow about the tube end is inconsistent with the entry of the water into the tube. When valve element 80 seats, however, the kinetic energy of water flow is transformed substantially wholly to static head pressure, with the result that water returns to the dishwasher vat through tube 90. This operation may, of course, occur at any stage of dishwasher action; conceivably, the stoppage and resulting return flow could occur at the very outset of dishwasher operation. The time-cycle mechanism 6 would nevertheless continue to operate and at the established intervals set up the electrical circuits to admit water to the vat and to close the motor circuit. However, the measuring coil of the above-noted Merrill patent would maintain its established control of the water inlet valve mechanism; and since no water is being drawn, the motor load remains at the level at which the measuring coil operates to close the inlet valve. It is therefore impossible to overload the motor by excess water in the vat even though drainage is blocked.

As earlier stated, the liquid pumping action provided by elements such as the sectors 32 appear to produce a more positive drainage control, although a relatively smooth-walled hub below the blades 18 is also effective. Therefore, while there has been described what is at present considered to be the preferred embodiments of the invention, it will be understood that various modifications may be made therein, and it is intended to cover in the appended claim all such modifications as fall within the true spirit and scope of the invention.

I claim:

In a dishwasher, a vat, means for introducing a quantity of liquid thereto, an impeller in said vat for distributing said liquid thereabout, a sump below said vat and communicating therewith through at least one opening in the bottom of the vat, pumping means disposed within said vat to intercept liquid flowing to said opening and direct it away from said opening, pumping means in said sump, a motor common to said impeller and said two pumping means to operate the same, means for controlling the periods of operation of said motor, a discharge line from said sump rising to a downwardly extending outlet for discharge into a plumbing waste line or the like, valve means upstream of said point of discharge and arranged to close against backflow of liquid 15

from said waste line into said discharge line, and tubular means communicating between said discharge line and said vat to return pump discharge to said vat in the circumstance of operation of said motor while said valve 5 means is in closed position.
